ASPIRATOR UNIT

Anthony J. Nastus, 79 Loretta St.,
New Brunswick, N.J. 08902

Filed Jan. 18, 1971, Ser. No. 107,611

Term of patent 14 years

Int. Cl. D24—02

U.S. Cl. D24—1 D

FIG. 1 is a top perspective view of the aspirator unit;
FIG. 2 is a bottom perspective view of the aspirator unit;

FIG. 3 is a side view of the aspirator unit;

FIG. 4 is a top plan view of the aspirator unit; and

FIG. 5 is a side elevation of a modified embodiment of the aspirator unit illustrated in FIG. 1; the broken lines representing the container are shown for illustrative purposes only.

I claim:

The ornamental design for the aspirator unit, as shown and described.
